UNITED STATES PATENT OFFICE.

FRANKLIN E. ARNDT, OF GALION, OHIO, ASSIGNOR TO THE GALION IRON WORKS AND MANUFACTURING COMPANY, OF GALION, OHIO.

CUT-OFF GATE AND SPOUT FOR DISCHARGE-CHUTES.

1,135,980.

Specification of Letters Patent.

Patented Apr. 20, 1915.

Application filed April 8, 1914. Serial No. 830,469.

To all whom it may concern:

Be it known that I, FRANKLIN E. ARNDT, citizen of the United States, residing at Galion, in the county of Crawford and State 5 of Ohio, have invented certain new and useful Improvements in Cut-Off Gates and Spouts for Discharge-Chutes, of which the following is a specification.

My invention relates to unloading mechanism wherein a chute is employed, and particularly to means for controlling the discharge of material from said chute.

In the form of unloading mechanism on which my device is an improvement, there 15 is provided a chute whose discharge end is controlled by means of a pivoted spout. There is also provided a bucket into which the spout discharges, and in order to permit the upward movement of the bucket and at 20 the same time cut off the discharge of material from the spout, the spout is turned upward. It has been found in practice that this pivoted spout becomes clogged by the material discharged into it by the chute and 25 is very often prevented from being lifted up, and furthermore while the spout is being turned to its upward position, the material in the chute is liable to dribble from the spout thus causing a waste of the material. 30 It has also been found that it is difficult for the operator to gage the precise moment at which the spout should be turned in order to cut off the flow of material from said spout. If the spout is turned too soon, the bucket 35 will not be properly filled, and if the operator waits until the bucket is filled before turning up the spout, too much material is liable to flow into the bucket. Furthermore, if the spout is jammed in its downwardly 40 turned position or its upward movement impeded, the spout will prevent the upward movement of the bucket and is liable to be broken.

The object of my invention is to obviate 45 these difficulties by providing in conjunction with the pivoted spout before named, an independently operable cut-off.

A further object of the invention is to so construct the cut-off that it will be rigid 50 in use, will not bend or break, and will be so constructed that it may be easily passed through material such as coal, gravel or broken rock.

Still another object of the invention is to 55 form this cut-off in a very simple manner

and provide it with guides wherein it is operable, the guides being so formed that the chance of damage to the spout will be minimized.

Other objects will appear in the course of 60 the following description.

My invention is illustrated in the accompanying drawings wherein:

Figure 1 is an elevation of my discharge chute controlling apparatus, part of the 65 hoisting mechanism and the bin into which the bucket discharges, the ground below the bin being in section to show the pit. Fig. 2 is a front elevation of the forward end of the chute, the levers whereby the controlling 70 spout and cut-off are operated and the frame for supporting said levers. Fig. 3 is a cross section on the line 3—3 of Fig. 2. Fig. 4 is a vertical section through the forward end of the discharge chute. 75

Corresponding and like parts are referred to in the following description and indicated in all the views of the accompanying drawings by the same reference characters.

I have illustrated in the drawings my 80 improvements as applied to an unloading and hoisting mechanism such as is illustrated in detail, and fully described in my pending application, Serial No. 830,470, filed simultaneously herewith. This unloading and hoisting mechanism is designed to be used with tracks over which dumping cars run, these tracks being designated 2. At a suitable point alongside the tracks 85 there is provided a bin 3 supported upon posts 4 or in any other suitable manner and of any suitable construction. Disposed beneath the tracks 2 is the chute 5 which extends downward and toward the bin and whose inclined bottom discharges into a pit 90 7. A hoisting mechanism is connected to a bucket 8, this hoisting mechanism being of such a character that the bucket may be hoisted and dumped into the bin and then returned to its original position in the bottom of the pit. The particular form of hoisting means and particular form of bucket forms no part of my present invention and therefore the hoisting mechanism and the bucket need no further detailed 95 description.

The bottom of the chute 5 extends somewhat into the pit 7 and the front end of the chute is partially closed by a vertical wall 9. This wall is formed of a sheet of metal 10 110

which is flanged at its ends as at 11 and riveted to the side walls of the chute. A second sheet of metal 12 is disposed parallel to and in spaced relation to the sheet 10 and 5 is likewise flanged at its ends and riveted to the side walls of the chute. This front wall which is formed by the two sheets of metal 10 and 12 extends down from the top of the chute to a suitable distance from the bottom 10 thereof, the space between the lower edge of the end wall and the bottom forming a discharge opening designated 13.

The cut-off 14 which operates between the sheet metal plates 10 and 12 has a height considerably greater than the height of the opening 13 and has a width equal to the width of the opening 13. This cut-off 14 is preferably made of a vertically corrugated sheet of metal, the corrugations having a depth approximately equal to the space between the plates 10 and 12 so that the crest of alternate corrugations will bear upon the plates 10 and 12 and thus hold the gate from any lateral play while permitting 20 it to easily slide between the guides formed by the plates 10 and 12. A rod 15 extends downward against the plate 14 and is nested within one of the corrugations, the upper 25 end of the rod being formed with an eye 30 and being connected through this eye to a link 16. This link 16 is loosely connected to a lever 17. A frame 18 is provided comprising the laterally disposed upwardly extending standards 19 and 20. The lever 17 35 is pivoted to the standard 20 and extends beyond the standard 19. A hook 21 or other support is formed upon the standard 19 upon which the lever rests when the lever is raised.

The standards 19 and 20 at their lower 40 ends are connected by transverse boards 22 hingedly connected at 23 to a base-board 24 which is adapted to rest upon the upper faces of the ties on which the track 2 is mounted. It will be seen that by depressing 45 the lever 17, the cut-off will be depressed so as to close the discharge opening 13 and that by raising the lever, the cut-off is lifted to expose the discharge opening.

Pivoted to the lower end of the chute 5 is 50 the U-shaped spout 25. This spout is approximately U-shaped in cross section and at its rear end is braced by a transverse angle iron 26. As illustrated in Fig. 1, the spout when turned down extends nearly to 55 the middle of the pit 7 and discharges into the middle of the bucket 8 when the bucket is in the bottom of the pit. When this spout is turned upward to the position shown in Fig. 4, the bottom of the spout extends at 60 right angles to the bottom of the chute 5 so as to permit the bucket when it is drawn upward and laterally to clear the spout.

For the purpose of operating the spout, I 65 provide the lever 27 which is pivoted upon the upper end of the upright 20 and which

is adapted to engage over the hook 28 formed upon the upright 19. A yoke 29 is pivotally connected to the forward end of the spout and is in turn connected to a link 30 which at its upper end is loosely connected 70 by means of the U-bolts 31 to the lever 27. Thus by lifting the lever upward, the spout may be raised to its closed position and by lowering the lever the spout may be dropped to its discharging position. 75

The operation of my invention will be obvious from what has gone before. When a bucket has been lowered into the bottom of the pit 7, the bucket being guided into proper position by the inclined wall 7a of 80 the pit, the spout 25 is first lowered to its discharging position and then the cut-off gate 14 raised. The contents of the chute will now be discharged from the spout into the bucket. When the operator sees that 85 the bucket is nearly filled, he lowers the cut-off gate thus cutting off the further discharge of material into the spout and then raises the spout permitting the bucket to be raised. The spout remains raised of course 90 until the bucket is returned to its position in the bottom of the pit whereupon the operation is repeated.

It will be noted that the frame composed 95 of the members 19, 20 and the boards 22 is hinged to the base member 24. The boards 22 act as a partition when the frame is in a vertical position, preventing crushed stone, coal or other material being discharged from the cars from rolling into the pit 7. When, 100 however, the cars are being switched or reset, the frame may be turned down into position over the pit thus not only getting this frame out of the way, but covering the pit and forming a platform over it. 105

It will be noted that the corrugated cut-off permits the hinged or pivoted spout to be operated freely after the flow of material has been cut off, and that inasmuch as the flow of material has been cut off prior to the 110 complete filling of the bucket, the comparatively little material which will remain in the spout after the closing of the cut-off will only act to fill the bucket and that therefore there will be no excess of material which will 115 drop into the bottom of the pit and tend to fill it.

The use of a corrugated plate for forming the cut-off has a number of advantages. 120 The vertical corrugations stiffen the plate in the direction of its operation. At the same time the corrugations of the plate permit the plate to fit around particles of coarse gravel or the pieces of broken rock or coal forming the material through which the gate passes. If the plate were straight and not corrugated, pits of rock or like material which were disposed immediately beneath the gate would block its downward course 125 but the sinuous curve of the corrugated 130

metal tends to wedge these pieces out of the way and the corrugations in practice work through the interspaces between the pieces of rock or coal. A further advantage lies in 5 the fact that the crests of the corrugations contact on each side with the plates 10 and 12 as heretofore described and thus these plates act to guide the gate without however causing the gate to bind. If the plate 14 10 were flat, the guides would have to fit the plate relatively snugly and there would be great liability to bind. This is overcome by the use of the corrugated plate. By using a corrugated plate, the necessity of bracing 15 the plate 14 is done away with and thus the plate may be very simply and cheaply made.

It will be seen that the frame supporting the levers and supporting the boards 22 is held in a vertical position by means of the 20 braces 33 which are pivoted to the ends of the frame and engage pins 32 projecting from the sides of the pit.

My improved mechanism is found to be very advantageous as a means for unloading 25 material such as crushed stone, coal, etc., from the cars and elevating it into a bin where it may remain until discharged into wagons. The mechanism is such that it may be easily controlled by one or two operators 30 and it is so simple that there is nothing to get out of order. By the use of the combined spout and cut-off, none of the material being loaded will scatter into the bottom of the pit and this is particularly important as 35 otherwise a great deal of time is lost in clearing out the pit and keeping it free from lumps of material so that the bucket may move downward to the bottom of the pit and be supported in proper position to receive 40 the material. Furthermore, by the use of the combined cut-off and spout, it is possible to fill the bucket to its capacity without any danger of the contents of the bucket overflowing into the pit. When merely a 45 spout is used, there is liability of the operator either filling the bucket too full so that it overflows or not filling the bucket to capacity. In either case, time is lost.

What I claim is:

50 1. The combination with a discharge chute, of a spout pivotally connected to the discharge end of the chute and rotatable in a vertical plane, spaced guide plates disposed at the discharge end of the chute and closing the upper portion of the same, a sliding cut-off disposed between said plates, and means for independently operating the cut-off and the spout.

60 2. The combination with a discharge chute, of a vertically sliding cut-off therefor disposed at the discharge end of the chute, said cut-off consisting of a vertically corrugated plate.

65 3. The combination with a discharge chute, of vertically disposed spaced plates

located at the discharge end of the chute, and a cut-off disposed and movable between said plates, the cut-off being vertically corrugated, the depth of the corrugations being approximately equal to the space between said plates. 70

4. The combination with a discharge chute, of transversely extending spaced plates disposed vertically across its discharge end, the lower edges of the plates being 75 spaced above the bottom of the chute, a spout pivoted to the chute at the discharge end thereof outward of said plates, a vertically corrugated cut-off plate disposed between the spaced plates and movable vertically 80 therein, the depth of the corrugations of said cut-off being approximately equal to the space between the plates, and means for independently operating either the spout or the cut-off. 85

5. The combination with a discharge chute, of a frame supported above the discharge end of the chute comprising a basal portion and upright posts, transversely extending spaced guide plates disposed at the 90 discharge end of the chute below said frame, a vertically corrugated cut-off movable between said plates and guided thereby, a spout pivoted to the chute at the discharge end thereof outward of said cut-off, levers 95 mounted upon one of said posts, supports on the posts for holding the levers in a raised position, and links connecting said levers respectively with the cut-off and spout. 100

6. In an apparatus of the character described, the combination with a chute, of a spout pivotally connected to the discharge end of the chute and adapted to be rotated in a vertical plane, a cut-off disposed inward 105 of said spout and vertically movable, a supporting frame disposed above the discharge chute, and means on the supporting frame for independently operating the spout and the cut-off. 110

7. In an apparatus of the character described, the combination with a chute open at its top and discharging at one end, of a spout pivoted to the end of the chute for vertical movement, spaced guide plates extending transversely across the chute and disposed above the bottom thereof at the discharge end, a vertically corrugated cut-off movable between said guide plates, the corrugations of said cut-off being equal to 120 the space between said plates, a frame mounted above the discharge end of the chute, a base plate to which said frame is hinged for vertical movement, a vertical partition carried by said frame, and levers mounted upon 125 said frame and operatively connected to the spout and cut-off.

8. The combination with a chute, of spaced guide plates extending across the upper portion of the outlet end of the chute, a verti- 130

cally movable gate slidably mounted between said plates and provided on its opposite faces with vertically disposed projections bearing upon said guide plates, and means 5 for operating said gate.

9. The combination with a chute, of spaced guide plates extending across the upper portion of the outlet end of the chute, a vertically movable gate slidably mounted between 10 said guide plates and provided on its opposite faces with vertically disposed projections bearing upon the guide plates, the projections on one face of the gate alternating with the projections on the opposite face 15 thereof, and means for operating said gate.

10. The combination with a chute, of spaced guide plates extending across the up-

per portion of the outlet end of the chute, a vertically movable gate slidably mounted between said guide plates and provided on 20 its opposite faces with vertically disposed projections bearing upon the guide plates, said projections extending the full height of the gate and the projections on one side of the gate being disposed alternately with 25 the projections on the opposite side thereof, and means for operating said gate.

In testimony whereof I affix my signature in presence of two witnesses.
